UNITED STATES PATENT OFFICE.

LOUIS BURL CLINTON, OF DURANT, OKLAHOMA.

WELL DRILL.

Application filed May 2, 1925. Serial No. 27,486.

To all whom it may concern:

Be it known that I, LOUIS BURL CLINTON, a citizen of the United States, residing at Durant, in the county of Bryan and State 5 of Oklahoma, have invented certain new and useful Improvements in Well Drills, of which the following is a specification, reference being had therein to the accompanying drawings.

10 This invention relates to rotary well-drills, and particularly to those of the kind that form a core that is removed for examination to ascertain the character of the material through which the drilling is performed.

15 It is an object of the invention to provide a drill device so arranged that its drill-bit will form a core somewhat smaller than the barrel to which it is attached, so that the 20 core will be retained practically intact in the barrel, in order that it may exhibit the strata and other characteristics of the formations from which it is taken.

25 Another object of the invention is so to arrange a valve in the barrel that a core can move upwardly past it without rupture and which retains the core and other matter in the barrel until it is withdrawn.

30 Still another object of the invention is to provide a device of this character so arranged that water in sufficient quantities is supplied to the drill-bit from the drill-stem to which the device is connected.

35 When considered with the description herein, the characteristics of the invention are apparent from the accompanying drawings, forming part hereof, wherein an embodiment is disclosed, for purposes of illustration.

40 Although the disclosures exemplify what now is considered to be a preferable embodiment of the invention, it is to be understood that it is not the intention to be limited necessarily thereto in interpretation 45 of the claims, as modifications and adaptations within the limits of the claims can be made without departing from the nature of the invention.

50 Like reference-characters refer to corresponding parts in the views of the drawings, of which—

Fig. 1 is a longitudinal section;

55 Fig. 2 is a view of the drill-bit in elevation and of the lower portion of the barrel in section;

Fig. 3 is a section on the line 3—3, Fig. 1;

Fig. 4 is a section on the line 4—4, Fig. 1; Fig. 5 is a view of the valve;

Fig. 6 is an end view of the drill-bit.

The device includes a drill-bit having a 60 body 7, from which teeth 8 extend downwardly. The peripheral surface of the teeth and body tapers slightly from the bottom toward the top, to avoid binding in the drilled hole. A substantially vertical passage or chamber 9 extends through the bit and inside of the teeth, which are arranged therearound, and the passage tapers from between the teeth to a slightly larger diameter toward the top, to prevent binding of 65 the cut core therein. The teeth curve downwardly and forwardly and taper to their lower or cutting edges, and this curved formation is such that as the tooth material wears the cutting edges at the same time are sharpened. A peripheral groove 10 extends upwardly from in front of each tooth to permit upward movement of cuttings.

The upper end of the bit has an annular 70 channel or groove 11, from which water-passages 12 lead to places of discharge between the teeth. An exteriorly-threaded nipple 13 positioned inside of the channel extends upwardly from the bit body, and it is arranged to be screwed into the interiorly-threaded power end portion of a core-barrel 75 14, whereby the bit is connected thereto.

The core-barrel is of slightly less exterior 80 diameter and of slightly larger interior diameter than the drill-bit, whereby cuttings and other matter passing upwardly outside of the bit may continue movement in the hole outside of the barrel and whereby the core formed inside of the bit may move 85 freely and intact into the barrel. The lower end of the barrel, after the nipple is screwed home, seats snugly against the upper end of the bit and covers the channel 11, and in its wall there are water-passages 90 15 extending from its upper end to the channel.

A clip 16 on the exterior of the barrel extends across an elongated longitudinal seat or groove 17 in the barrel. The seat accommodates an arm 18, which normally is held in place by the clip, and extends at an angle from and is a part of the valve-stem 19. The stem extends into the wall of the barrel in secant disposition with respect to the periphery thereof, and a valve 20 is mounted swingably on the intermediate portion 100 of the stem and extends upwardly 110

therefrom. The valve is made of strong sheet metal, it is of approximately elliptical shape so that its edge may close against the inner surface of the barrel when it is disposed at an inclination to the axis, and it is curved transversely so that it may lie closely against the barrel when it opens upwardly, whereby a substantially intact core may move past the valve. The valve is kept normally closed by a spring 21, which in the form shown is attached at one end to the valve near the stem and bears at the other end against the barrel.

Vents 22 extend from the interior to the exterior of the barrel near its upper end, to permit exit from the barrel of soft mud, water, etc., that may pass the valve or collect while lowering the device into a well.

The vents also permit exit of such matter while a core is being formed and as it moves into the barrel. The barrel is threaded interiorly above the vents to hold therein an exteriorly-threaded plug 23. The barrel is exteriorly threaded at its upper end, whereby it may be connected to an interiorly-threaded lower end of a drill-stem 24. Water is supplied to the device through such a stem, and the plug prevents its passage into the interior of the barrel and causes it to seek outlet through the longitudinal passages 15 of the barrel to the bit. The water thus supplied to the bit keeps it cool, softens material through which the bit is working, and washes the cuttings upwardly to the exterior of the barrel.

For the usual run of operations for the taking of a core as a sample of the formations through which a well is being driven, the barrel is some twenty feet long, and the device is arranged to take a core of almost the length of the barrel and to keep it intact until it can be withdrawn from the well and removed from the barrel for examination. The spring of the valve is arranged to yield to permit the valve to open entirely as the core presses thereagainst and moves past it, and the spring is of such strength that it

causes the valve to press against the side of the core just enough to prevent it from descending out of the barrel, while the latter is being withdrawn from a well, without breaking it. The valve also prevents descent of other matter that may accumulate in the barrel and causes it to seek exit through the vents.

After the barrel has been withdrawn from a well, and it is desired to remove the core from its bottom rather than from its top, the valve may be released by releasing the hold of the clip 16 on the arm 18, pulling that arm outwardly of the seat 17, and then pulling the stem 19 out of the barrel. Then the valve is free to fall out of the barrel ahead of the core. After the core is withdrawn, and when the device is to be made ready for another drilling operation, the valve is replaced in the barrel and the stem inserted and locked in its normal position.

Having thus described my invention, what I claim as new, and desire to secure by Letters Patent, is—

A well-drill device comprising the combination of a drill-bit having teeth extending downwardly from its body, a vertical central passage, an annular water channel in its top, water-passages leading from said channel to spaces between said teeth, and an upwardly-extending nipple inside of said channel; a barrel abutting against the top of said drill-bit, connected thereto by said nipple, containing longitudinal water-passages leading to said channel, and having a vent extending from the interior to the exterior of its upper portion; a removable plug above said vent; an upwardly-opening valve in the lower portion of said barrel arranged when open to lie closely against its wall; and means whereby a hollow drill-stem is secured to the upper portion of said barrel in communication with the water-passages therein.

In testimony whereof I affix my signature.

LOUIS BURL CLINTON.
